WILHELM ARNO MAX HOFFMEISTER, OF NEUSTADT, GERMANY

APPARATUS FOR AND METHOD OF PARAFFINING MATERIAL

Application filed February 8, 1928, Serial No. 338,387, and in Germany June 6, 1928.

The present invention relates to improvements in the apparatus for and method of paraffining material.

As is well known artificial leaves employed in the manufacture of flowers, after they have been stamped or cut out and furnished with a stem, are finished by applying a coating of paraffin thereto. The paraffining in the known processes is accomplished by tying together the ends of the stems of a number of leaves, then dipping the leaf bunches so formed into a liquid paraffin bath and then transferring the dipped bunches for mechanical treatment to an apparatus where by means of centrifugal force, the excess paraffin is removed from said bunches. Immediately thereafter the bunches of the thus treated leaves must be rapidly separated in order to prevent individual leaves from sticking together. A great part of this process has been hitherto accomplished by manual means.

This awkward process is simplified by the present invention and manual operations are eliminated to a marked degree. According to my invention loose leaves, chosen at random from a batch to be treated, are passed to a conveyor which first conveys the said leaves through a paraffin bath, thence through means such as press rollers where the excess paraffin accumulated by said leaves is removed and thence to an automatic leaf separator.

With my new method it is possible to place leaves, chosen at random on a conveyor, it being immaterial whether or not several leaves happen to lie one on top of the other, provided however that care is taken that the conveyor carries all the leaves thereon through the paraffin bath and that none is allowed to merely float on the surface of said paraffin bath. The same conveyor further carries the leaves out of the bath, and leads them to a device for removing excess paraffin accumulated thereon and then to a leaf separating device associated with said paraffin removing device.

In carrying out my invention leaves may be placed, for example, between opposite surfaces of the flights of two endless conveyor

bands, said flights being adapted to pass through a paraffin bath during a portion of their path of travel. The leaves may then be further conveyed by the said flights to a paraffin removing device comprising for instance two press rollers, yieldingly held together under pressure, so that paraffined leaves passing between said rollers will have excess paraffin expressed therefrom.

The separating device associated directly with said expressing device may for example be driven by compressed air which will whirl the leaves against rebounding surfaces. Said separation device may also be a rapidly moving or rotating beater onto which the leaves are transferred.

Thus with my new process, collecting, straightening out, tying in bundles, and subsequently separating and untying can be entirely eliminated and manual labor entirely replaced by mechanical labor whereby the leaves picked at random from a batch are passed to the conveyor. Even the passing or feeding of the leaves to the conveyor may be accomplished by mechanical means, if desired.

My invention will be more fully understood by reference to the accompanying drawings in which similar reference characters denote corresponding parts and in which

Fig. 1 is a diagrammatic vertical section of one form of my device and

Figs. 1a and 2a are plan views of Figs. 1 and 2 respectively.

Fig. 2 is a similar view of a second form.

According to Fig. 1 the leaves A are transferred to a slanting chute 1 and thence to a conveyor consisting of an endless band 2 of pervious or porous material and which is guided over guide rollers 3, 4, and 5 that revolve in the direction of the arrows X shown in the figure. The flight 2' of this conveyor is in range of the lower section of a drum 6 which rotates in the direction of the arrow Y, and contacts with a greater part of the surface of said drum, care being taken that only a moderate pressure is exerted by said flight against the drum surface, so as to permit the passage of leaves between said flight and

drum surface even when several are piled one on top of the other.

The drum 6 which is driven by suitable means is provided with a layer of soft material, such as felt, and dips in the paraffin bath contained in a receptacle 8, so that a part of the flight 2' is also submerged in the paraffin bath.

The leaves A fed through the chute 1 are caught by the conveyor and carried along by the latter to the drum 6 and between the flight 2' and the felt layer 7 of the said drum 6. The endless band is adapted to be driven with the surface speed of the drum 6 by suitable means, not shown, the leaves being positively carried along due to the frictional engagement of said leaves between said drum surface 7 and said flight surface 2'.

The guide roller 5 is adapted to function as a press roller and is adjustably mounted outside of the paraffin bath in such manner that it can be made to bear against the drum 6 with any desired pressure. The means for so mounting said roller may be any of the well known type, such as an adjustable bearing for the shaft of said roller, or the like. The paraffined leaves moving along the flight 2' pass between said guide roller 5 and drum 6 and due to the pressure excess paraffin is expressed therefrom. The leaves emerging from the roller 5 are then transferred to a leaf separating device which may comprise a plurality of surface beaters 10 arranged star like on a shaft 9, capable of comparatively rapid rotation and driven by any suitable means, not shown, for instance by being belted in suitable speed ratio to the drive of the drum 6. The beaters are mounted so as to be adjacent the roller 5 whereby as leaves emerge from between the drum 6 and roller 5 the mechanical action of said beaters causes any leaves that tend to stick together to separate and be whirled into the air. The leaves are then subjected to a cooling air current fed from a suitable source 14, in direction of the arrows Z, in order that they drop into a collecting receptacle 15 in a sufficiently cooled condition and be thereby prevented from sticking together.

According to the modification shown in Fig. 2 there is a chute 1 as before for transferring leaves A fed therethrough to a guide surface 11 which consists of a thin sheet of metal or the like curved to adapt itself concentrically to the lower surface of the drum 6. A narrow space is provided between said surface 11 and the drum surface for the passage therethrough of the leaves.

As before the drum 6 is provided with an absorbent covering or layer of felt 7 or the like and dips into the paraffin contents of container 8. The press roller 5' which in its operation is identical with that of roller 5 and has the same adjustable features as in this modification is provided with a felt covering

52. The beating surfaces 10 on shaft 9 rotating in the same manner as before are also present in this device.

The guide surface 11 in this modification does not move longitudinally but is provided at one end thereof with suitable tension adjustment means 13 carrying bolts 13', slidably adjustable in slots 8' provided in an upwardly projecting slanting flange 8' of the container 8.

The receptacle 8 for the paraffin is of such dimensions that the drum 6 does not reach to the side walls thereof, so that the paraffin can readily drop into the space between the surface 7 and guide surface 11.

My invention may be modified without departing from the spirit thereof and I do not wish to be limited by the details shown and described.

What I claim is:

1. In a process of paraffining artificial leaves, the steps of continuously feeding leaves, chosen at random, along a path leading through a paraffin bath and outwardly from said bath, then causing excess paraffin accumulated thereon to be expressed from said leaves while passing out from said bath and subsequently causing said leaves to be subjected to beating action before said paraffin has cooled whereby said paraffined leaves become separated from one another.

2. In a process of paraffining artificial leaves, the steps of continuously feeding leaves, chosen at random, along a path leading through a paraffin bath, and outwardly from said bath, then causing excess paraffin accumulated thereon to be expressed from said leaves, then subjecting said paraffined leaves to beating action whereby they become separated, and then cooling said leaves.

3. A device for preserving artificial leaves comprising in combination, a receptacle for a liquid paraffin bath, means for continuously feeding leaves through and out of said liquid, means close to the exit point from the liquid bath for expressing from said leaves excess liquid accumulated thereon as said leaves emerge from said bath and means for immediately separating said leaves, said means for separating the paraffined leaves including movable beating means.

4. A device for preserving artificial leaves comprising in combination, a receptacle for a liquid paraffin bath, means for continuously feeding leaves through and out of said liquid, means close to the exit point from the liquid bath for expressing from said leaves excess liquid accumulated thereon as said leaves emerge from said bath and means for immediately separating said leaves, said means for separating the paraffined leaves including a rapidly revolving member formed with a plurality of beaters.

5. A device for paraffining artificial leaves comprising in combination, a recep-

tacle for a liquid paraffin bath, a rotatable drum in said receptacle adapted to be partly submerged in the contents thereof, an endless band adapted to cooperate with said drum and extend concentrically over a considerable segment of the circumference of said drum, rollers for so mounting said band, one of said rollers being mounted above the liquid level of said receptacle and adjacent the point of emergence of said leaves from said bath, said last named roller being so located relative to said drum as to act therewith by pressure to express excess paraffin from the said leaves, and a rotatable beater mounted adjacent said last named roller and adapted to separate said leaves from each other as they emerge from the expressing treatment and before the paraffin has cooled.

6. A device as per claim 5, in which means for receiving said separated leaves and means for cooling said separated leaves before they reach said receiving means are provided.

In testimony whereof I affix my signature.
WILHELM ARNO MAX HOFFMEISTER.
